[57] CLAIM

The ornamental design for a flashlight holder with living hinge, as shown and described.

DESCRIPTION

FIG. 1 is a perspective view of the flashlight holder with living hinge showing my new design, the hinge being bent to hold a flashlight in a vertical position, the flashlight being shown in broken lines for illustrative purposes only;

FIG. 2 is a front elevational view of the flashlight holder with living hinge in a flat position;

FIG. 3 is a rear elevational view thereof;

FIG. 4 is a bottom plan view thereof;

FIG. 5 is a top plan view thereof; and,

FIG. 6 is a side elevational view thereof (the other side corresponds).

FIG. 1

FIG. 6

FIG. 2

FIG. 3

FIG. 4
